TAPE PERFORATING APPARATUS

Ward Leathers, Brooklyn, N. Y., assignor to International Business Machines Corporation, New York, N. Y., a corporation of New York

Application July 23, 1942, Serial No. 452,049

9 Claims. (Cl. 164—112)

The improved tape perforating apparatus comprising the present invention is primarily adapted for use in connection with the perforating of a continuous strip of tape according to a selected code, which may, if desired, be the "Tele-lector" code system shown in an application for U. S. Letters Patent to Ward Leathers, Serial No. 349,975, filed August 2, 1940, for "Meter reading apparatus." In this code system an elongated strip of tape is perforated in each of a series of successive index point positions by a four-line series of perforations. The invention, however, is susceptible to modification and the principles of the same may be employed in the perforation of a continuous strip of tape regardless of the specific code employed or of the number of lines of perforations employed thereby.

The principal object of the present invention is to provide a unitary, compact perforating apparatus which is extremely efficient in its operation and which employs a series of solenoids for operating the actual tape perforating punches, the solenoids and punches being operatively associated with one another in such a manner that a more positive and rapid punching operation is attained than has heretofore been made possible in connection with solenoid actuated punches. Toward this end the invention contemplates the provision of a series of solenoid actuated punches, wherein the armature of each solenoid magnet normally is maintained spaced from the punch actuating device whose movements it controls, so that upon energization of the magnet a hammer effect is obtained by the armature on the punch-operating mechanism, and the armature is caused to recoil under the impetus of the impact so as to clear itself from the return stroke of the punch-operating mechanism and thus permit this latter mechanism to effectively and rapidly clear the tape.

An additional object of the invention is to provide a solenoid actuated tape perforating mechanism of the character set forth above, wherein there is employed a single solenoid for operating the driving mechanism for the tape and a single solenoid is employed for applying drive perforations thereto, the two solenoids being mechanically and electrically interconnected for positive simultaneous actuation thereof.

Another object of the invention is to provide a solenoid actuated tape perforating apparatus wherein the perforating punches are actuated in an extremely efficient and positive manner so that there will be a minimum of error or failure on the part of the punches.

Another object of the invention is to provide an apparatus of this character wherein the stroke of the punches may be varied to accommodate tape having different characteristics.

5 Another object of the invention in a machine of this character is to provide a novel and extremely efficient tape receiving chuck having means associated therewith for ejecting a roll of tape from the chuck without the necessity of exerting manual force on the roll which might tend to distort the roll.

10 Another object of the invention in this type of machine is to provide a novel and efficient method of disposing of the tape punchings or "chips" (as they are called) and toward this end the invention contemplates the provision of a vacuum or suction device for withdrawing the chips from the vicinity of the perforating station.

15 Yet another object of the invention is to provide a novel and efficient form of tape guiding means having associated therewith tape tensioning means for holding the tape taut in the straightaway portion thereof.

20 25 A still further object of the invention is to provide an improved form of pressure device for holding the tape firmly against the bed plate during the tape perforating operations and for releasing the tape completely from its driving connection in the machine when the tape perforating operations have been concluded.

30 35 Still another object of the invention is to provide a tape perforating apparatus in which the tape although intermittently advanced through the machine is positively and firmly handled while at the same time no excess tension or binding of the tape is encountered, thus contributing toward a completely perforated tape which is free from tears, rips and other defects of this nature.

40 45 50 A further object of the invention is to provide a tape perforating apparatus having means for normally advancing the tape in one direction intermittently in order that perforations may be formed in the tape at the successive index point positions, and also having means for uniformly reversing the movement of the tape, the latter means being operative to render the former means ineffective when said latter means becomes effective.

The provision of an apparatus which is extremely simple in its construction; one which is comprised of a minimum number of moving parts and which, therefore, is unlikely to get out of order; one in which the various parts

thereof are duplications one of another and which parts may be constructed of relatively light sheet metal stampings thus contributing to economy of manufacture; and one which is efficient in its operation and is capable of efficiently performing the services required of it, are further desiderata that have been borne in mind in the production and development of the present invention.

In the accompanying two sheets of drawings comprising part of this specification:

Fig. 1 is a fragmentary side elevational view of a tape perforating apparatus constructed in accordance with the principles of the present invention.

Fig. 2 is a top plan thereof.

Fig. 3 is a detailed enlarged fragmentary side elevational view of a portion of the apparatus showing the tape advancing mechanism and other parts associated therewith.

Fig. 4 is a top plan view of the mechanism shown in Fig. 3.

Fig. 5 is a sectional view taken substantially along the line 5—5 of Fig. 3.

Fig. 6 is an enlarged sectional view taken substantially along the line 6—6 of Fig. 1.

Fig. 7 is a sectional view taken substantially along the line 7—7 of Fig. 6.

Fig. 8 is a fragmentary side elevational view of the tape reel holder showing a reel-ejecting mechanism associated therewith.

Fig. 9 is an end elevational view of the structure shown in Fig. 8.

Fig. 10 is a sectional view taken substantially along the line 10—10 of Fig. 1, and

Fig. 11 is a sectional view taken substantially along the line 11—11 of Fig. 1 in the direction indicated by the arrows.

Fig. 12 is a view of the spring tape lifter.

In all of the above described views like characters of reference are employed to designate like parts throughout.

The general appearance and arrangement of the apparatus is best illustrated in Figs. 1 and 2. The apparatus involves in its general organization a base portion 10 in the form of a generally rectilinear casing provided with an access opening 12 in the front wall thereof which is normally closed by means of a panel or door 14. The base portion is provided with an upper horizontal ledge or table portion 16 upon which there is mounted an intermediate casing 18 which also is generally of rectilinear design and which likewise is provided with an upper horizontal ledge or table portion 20. Seated upon the table portion 20 is an upper casing 22 in which there is housed the various tape punching and tape advancing instrumentalities by means of which the tape is perforated according to the selected code. The three casings 10, 18 and 22 are of progressively decreasing size and are arranged in superimposed relationship in pyramidal fashion, the height of the various casings being such that the upper casing 22 is at the proper level for the inspection and attention of an operator.

The lower casing 10 communicates interiorly with the intermediate casing 18 by means of an opening 24 and the two casings 10 and 18 serve jointly to house or enclose various operating instrumentalities for tensioning the tape, for winding or reeling the same, mechanism for withdrawing and disposing of the tape punchings or "chips," together with various electrical apparatus including coding mechanism for actuating the punches, circuit connections therefor and

for the driving motor, etc., such electrical apparatus not being shown in the accompanying drawings inasmuch as no claim is made herein to any novelty associated therewith.

5 The upper casing 22 is generally in the form of a relatively narrow box-like member having side walls 26, a rear wall 28, a bottom wall 29, and a front opening 30 adapted to be enclosed by means of a transparent inspection panel 32. The upper 10 corners of the casing 22 at opposite longitudinal ends thereof are cut away or inclined, as at 34, and mounted on the cut-away portions are a pair of roller guide assemblies 36, over which the tape T is adapted to pass. The roller guides 36 have 15 associated therewith tape tensioning devices 38 for holding the tape taut in the straightaway portion thereof. The tape T is supplied in the form of a roll 40, which is removably mounted upon a chuck 42 carried by a hollow bracket 44 mounted 20 upon the upper table portion 20, and also secured in any suitable manner to one of the side walls 26 of the casing 22. A similar hollow bracket 46 is mounted on the table portion 20 on the opposite side of the casing 22 and serves to support thereon a receiving chuck 48 to which the tape T is fed. The bracket 46 further serves to support 25 a third chuck assembly 50, similar to the chuck assembly 42, which is designed for reeling purposes, as will be described hereinafter.

30 Tape issuing from the roll 40 and passing over the roller guide 36 and beneath the tensioning device 38, passes over a bed plate 52 and through a perforating station 53 at which a series of perforations are punched in the tape according to the selected code. The bed plate 52 is mounted upon and serves to close the upper end of the casing 22.

Referring now to Figs. 3, 4 and 5, the bed plate 52 is in the form of a relatively thick steel plate 40 secured around its periphery to the turned upper rim 54 of the casing 22. Secured to the underneath side of the bed plate 52 is a frame-like member 56 having a transverse guide portion 58 associated therewith provided with a plurality 45 of vertical guideways 60 therein. While any suitable number of guideways 60 may be employed, in the present instance four such guideways 60 in alignment, and a fifth offset guideway 61 have been shown in the transverse guide portion 58. The central guideway 61 serves to slidably retain therein a tape perforating punch 62 for perforating a longitudinal series of center driving holes in the tape T. The remaining guideways 60 each serve to slidably retain therein 50 a tape perforating punch 64 which latter punches are for the purpose of perforating the code characters in the tape. The punch 62 may be of slightly smaller diameter than the punches 64 in order that the drive hole perforations in the tape may readily be distinguished from the code character perforations. A plurality of guideways 66 are formed in the bed plate 52 in alignment with the various guideways 60 provided in the transverse portion 58 of the frame member 56.

Secured to the upper side of the bed plate 52 and overlying the region of the guideways 60 and 61 is the punching die proper 70. The major portion of the die 70 is spaced above the upper surface of the bed plate 52 a distance substantially equal to the thickness of the tape T, and a plurality of die openings 72 (see Fig. 5) are formed in the die plate 70 in alignment with the various guideways 66.

75 A transparent inverted retaining member 74

is secured to and overlies the die plate 70 and is formed with a chamber or slot 76 therein for reception of the punchings or "chips," which are removed from the tape T. Means are provided for withdrawing the punchings or "chips" from the chamber 76 in a manner that will be more fully described hereinafter.

Because of the fact that the retaining member 74 is transparent, not only is the operator of the machine enabled to view the tape in the punching station to determine whether the chips are being efficiently removed or whether they have become clogged in the chamber, but also he is enabled to view that portion of the tape which is actually undergoing punching in order that he may read the characters appearing in the particular index point position directly above the row of punches. Thus, if for any reason whatsoever it is desired to stop the operation of the machine, as for example, when it is necessary to make a correction, it is unnecessary for him either to remove the retaining member 74 or to slide the tape from beneath this member to inspect the same.

Referring now to Figs. 3 and 5, a vertical support 78 extends upwardly from the bottom wall 29 of the casing 22 and terminates adjacent one edge of the bed plate 52 to which it is secured. The support 78 is provided with a horizontal upper guide portion 80 in the form of a lateral flange having guideways 82 formed therein through which the upper ends of a plurality of thrust rods 84 extend. The thrust rods 84 correspond in number to the number of punches 62, 64, and each rod 84 is in alignment with and bears at its upper end against the lower end of a respective punch. The support 78, in addition to the horizontal flange portion 80 is formed with flange portions 86, 88 and 90 at various heights within the casing 22. Two of the thrust rods 84 are relatively short and project downwardly through openings provided in the guide flange 86. An additional two of the thrust rods 84 are somewhat longer and project downwardly through openings provided in the horizontal flange 88. A third pair of the thrust rods 84 are relatively long and project downwardly through openings provided in the horizontal flange 90 carried on the support 78. Each of the thrust rods 84 is provided with a stop collar 92 which bears against the upper surface of one of the flanges 80, 86, 88 or 90, as the case may be, and limits the downward movement of its respective thrust rod. The lower end of each of the thrust rods 84 is formed with an adjustable abutment head 96 which is threadedly received thereon and which cooperates with a hammer or operating lever 98, the movements of which are electromagnetically controlled and by means of which the rod may be elevated to force one of the punches 62 or 64, as the case may be, upwardly into cooperative engagement with the punching die 70. Each abutment head 96 has associated therewith a locking nut 100 and thus it will be seen that by rotating the abutment head 96 relative to the thrust rod upon which it is mounted and then securing the same in its adjusted position by means of the lock nut 100, the effective length of the thrust rod may be varied to in turn vary the stroke of the punching die. The lower ends of each of the punching dies 62 or 64 are grooved as at 102 (see Figs. 3 and 5) and cooperating with each of the grooves 102 are a series of leaf springs 104 which are secured as at 106 to the underneath side of the frame 56 and the ends of which

5 springs are bifurcated for reception in the grooves 102. The springs 104 serve to provide a downward thrust or bias to the various punches 62, 64, and the punches, in turn, serve to maintain the thrust rods 84 in their lowermost positions with the various thrust collars 92 seated upon their respective retaining flanges 80, 86, 88 and 90.

10 Referring now to Fig. 1, a plurality of operating magnets designated at 110, 112, 114, 116, 118 and 120 are secured to the side walls 26 of the casing 22 interiorly thereof. The magnets 110, 114 and 118 are secured to one side wall 26 in superimposed relationship, while the magnets 112, 116 and 120 are similarly secured to the opposite 15 side wall 26. Each of the magnets 114, 116, 118 and 120, above referred to, is provided with an armature 122 having formed thereon an operating lever or hammer 98, above mentioned, the various levers having contact portions 126 underlying the various abutment heads 96 and remaining normally spaced therefrom a slight distance in order that upon energization of the magnets an initial free impetus will be imparted to the armature before actual engagement between the contact portions 126 and their respective abutment heads 96. Thus, it will be seen that the punches are actuated rather by a hammer effect than by a slow driving motion, thus resulting in very positive operation of the 20 punches.

25 30 The magnets 114, 116, 118 and 120 cooperate with the respective thrust rods 84 which, in turn, cooperate with the punches 64 for perforating code characters in the tape T. The magnet 110 is employed for tape driving purposes in a manner to be explained presently, while the magnet 112 cooperates with a thrust rod 84 that in turn cooperates with the central, hole tape perforating punch 62. The specific manner in which the 35 various magnets 110 to 120, inclusive, are operated is not material to the present invention and they may be energized in accordance with any accounting system utilizing a selected code, such as, for example, the Telelector code. In such an 40 instance, a coding mechanism designated in its 45 entirety at 129 in Fig. 1 may be installed in any suitable location within the lower pedestal or supporting casing 10 and it may be electrically connected to the various magnets 114, 116, 118 and 120 for proper cooperation therewith so that 50 when an input impulse is received by the coding mechanism one or more output impulses will be applied to the magnets to operate the same.

55 If desired, the apparatus may be controlled externally, i. e., it may be electrically connected by a system of cables to a remote control apparatus by means of which impulses are periodically applied to the coder. One instance of a 60 remote control system for the apparatus is shown in an application of Ward Leathers, Serial No. 349,982, filed August 2, 1940, for Automatic meter reading apparatus, wherein a plurality of meters located at a remote point serve to send signaling impulses to central station at which the present apparatus may be located. In such an instance where a remote control connection is provided, the lower casing 10 may have associated therewith a contact jack 131 for plug-in connections. In addition to provisions for 65 remotely controlling the apparatus, means are provided for manually controlling the same from a finger control panel such as is shown at 130. The panel 130 is preferably mounted on the ledge portion 16 of the lower casing 10 in front of and in close 70 proximity to the intermediate casing 18. This 75

panel may include a series of depressable buttons 132, one for each of the magnets 114, 116, 118 and 120 which control the character punches together with a spacing key 134 by means of which the magnet 110 that serves to drive the tape T may be energized. A button 136, for driving the magnet 121 by means of which the tape T is reversed, may be provided on the panel 130. Finally, the panel 130 may have associated therewith a starting switch 138. The various electrical connections between the control panel 130 and the operating instrumentalities contained within the casings 10, 18 and 22 have not been illustrated inasmuch as no claim is made herein to any novelty associated therewith. It is obvious that other forms of control panels may be employed, if desired, or if the machine is to be operated solely by remote control from some other apparatus, the control panel 130 may be omitted altogether. Irrespective, however, of these purely arbitrary details in the control of the operation of the machine the essential features of the invention are not destroyed.

Referring now to Fig. 3, a tape driving drum 140 is freely mounted for rotation upon a shaft 142, the opposite ends of which are journaled in the frame 56 immediately beneath the bed plate 52. The bed plate 52 is provided with an opening 144 therein into which the driving drum 140 extends. A plurality of tape driving pins 146 are spaced about the periphery of the driving drum 140 in radial fashion and these pins are of sufficient extent that their outer ends successively project slightly above the plane of the upper surface of the bed plate 52 upon rotation of the drum and extend into a series of driving perforations shown at d in Fig. 4 provided in the tape. Mounted on the shaft 142 at one side of the driving drum 140 is a ratchet wheel 148 having peripheral teeth 150 thereon corresponding in number to the number of driving pins 146. A follower 152 is pivoted as at 154 to a bracket 156 suspended from the underneath side of the bed plate 52. The outer end of the follower 152 is bifurcated as at 158 and carries between the bifurcations thereof a follower wheel 160. The follower 152 is spring pressed as at 162 in such a manner that the follower wheel 160 bears against adjacent teeth 151 of a ratchet wheel 153 and serves as a detent to limit the movement of the driving drum 140 so that the drum will normally occupy a position wherein one or another of the driving pins 146 is in registry with one of the perforations d in tape T.

In order to drive the tape advancing drum 140, the magnet 110 is provided with an armature 164 having an extension 166 thereon to which there is secured in any suitable manner, as for example, by means of cap screws 168, a spring biased pawl-carrying arm 170 provided with a pawl 172 adjacent its outer end. The member 170 is flexed under tension in such a manner that the pawl 172 thereof engages the periphery of the ratchet wheel 148 and cooperates with the teeth 150 thereof for driving purposes. The tension of the pawl-carrying spring arm 170 and the tension of the follower spring 162 is such that the pawl 172 may, upon energization of the magnet 110, move outwardly on the teeth 150 of the ratchet wheel 148 and snap into a preset position whereupon, after deenergization of the magnet 110, movement of the armature 164 to its normal position will serve to advance the ratchet wheel 148 and consequently the tape driving drum 140 throughout a predetermined arc to ad-

vance the tape T from one index point position to the next. In order to assist the armature 164 in returning to its normal position, a leaf spring 167 is secured by means of cap screws 169 to the underneath side of the magnet 110. The outer end of the leaf spring 167 bears against an adjustment nut 175 which is threadably received on a depending rod 171 suspended from an anchoring pin 173, the end of which is threaded into the armature 164. By properly adjusting the nut 175 the tension upon the armature 164 tending to restore the same to its normal position may be varied.

Under certain conditions of operation it may be necessary to reverse the movement of the tape or to back the same up, so to speak. To make this possible an additional ratchet wheel 176 having teeth 178 thereon disposed in reverse relation with respect to the teeth 150 of the ratchet 148 is mounted upon the shaft 142. The number of teeth 178 on the ratchet 176 corresponds in number to the number of teeth 150 and consequently to the number of driving pins 146 on the driving drum 140. In order to impart reverse rotation to the ratchet wheel 176 and consequently the driving drum 140, a pawl 180 is pivoted as at 182 to one end of a bell crank lever 184. The lever 184 is provided with a fulcrum 186 by means of which it is pivotally secured in the frame 56. The other end of the lever 184 is operatively connected as at 188 to the upper end of a connecting rod 190, the lower end of which is connected to the armature 192 (see Fig. 1) of the magnet 121 contained within the intermediate casing 18. The pawl 180 carries a roller 194 which bears against and freely rides upon the inclined side of the flexible pawl-carrying spring 170. Upon energization of the magnet 121, the thrust rod 190 will be moved downwardly, thus turning the bell crank lever 184 throughout a slight angle and causing the pawl 180 to ride upwardly on the spring 170 and engage the teeth 178 of the ratchet wheel 176. Further movement of the pawl 180 in its normal direction of travel will cause the same to become wedged between the periphery of the ratchet wheel 176 and the pawl-carrying spring 170, whereupon the latter spring will become flexed so that the pawl 172 moves out of engagement with the teeth 150 of the ratchet wheel 148, thus providing clearance in order that the pawl 180 may continue to move the wheel 176 and consequently the driving drum 140 throughout a predetermined increment of rotation to back up or reverse the movement of the tape. The tape will thus be projected rearwardly in step-by-step fashion through the slot existing between the bed plate 52 and the punching die 70 and become flexed in the straightaway portion existing between the punching die and the guide member 36. Under normal conditions of operation it will be unnecessary to reverse the tape more than a few index point positions and thus there will be little danger of the tape becoming excessively flexed in this straightaway portion. Upon resumption of operation of the machine, as, for example, when the spacing key 134 is depressed, the slack in the tape will be taken up automatically. If, however, under unusual conditions it is desired to reverse or back-up the tape to any considerable extent, means are provided for taking up any slack that ordinarily would exist in the straightaway portion thereof by reversing the driving connection to the chuck 42 in a manner that will be described presently.

The tape driving magnet 110 and the tape drive hole perforating magnet 112 are preferably electrically coupled in whatever circuit is utilized for operating the machine, whether it be a manually controlled circuit operable from the control panel 130 or whether it be a remote control circuit. These magnets are also electrically connected in parallel to each of the perforating magnets 114, 116, 118 and 120. By such an arrangement, whenever any tape perforating function whatsoever is performed by the apparatus or whenever a tape spacing operation is performed assurance is had that the tape will be properly perforated with a center drive hole perforation for subsequent registry with one of the pins 146 for driving purposes. As an additional precautionary measure, the two magnets 110 and 112 are mechanically coupled, as is clearly shown in Fig. 1. Toward this end, the hammer 98, which is in the form of an extension of the armature 122, is provided with a laterally extending flange 99 which underlies an extension 101 formed on the armature 164 of the magnet 110. Each time the tape drive hole perforating magnet 112 becomes energized to attract its armature 122, the flange 99 on the extension 98 will engage the extension 101 and assist in moving the armature 164 to its retracted position.

In order to remove the tape punchings or "chips" which are forced upwardly through the punching die 70 into the chamber 76, this latter chamber communicates through a hollow tubular rod 200 (see Fig. 1), the upper end of which projects upwardly through the punching die 70, with a receiving container 204 suitably mounted within the lower pedestal or base portion 16. A removable closure 202 through which the rod 200 passes is provided for purposes of access to the container. A degree of vacuum may be applied to the container 204 through the closure 202 by means of a suction pump 208 operatively associated through a driving connection with a motor M. Any suitable type of suction pump may be employed for this purpose. The motor M may be mounted upon a platform 210 contained within the intermediate casing 18. A jack shaft 212 rotatably mounted within the casing 18 is adapted to be driven by means of a belt 214 from the motor M. A belt 216 serves to operatively connect the jack shaft 212 and the pump 208.

In order to assist the drum 140 in advancing the tape from one index point position to the next, means are provided for constantly applying tension to the straightaway portion of the tape in the direction of its discharge onto the roll 41. Toward this end (see Fig. 10), the chuck 48 is provided with an extension 223 in the form of a stub shaft which projects through the hollow bracket 46 and is rotatably journaled in the opposite sides thereof. A pulley 225 is mounted upon the shaft 223 and an endless drive belt 227, preferably in the form of a helically wound spring, passes over the pulley 225 and is operatively connected to the motor M. The degree of tension applied to the drive belt 227 is such that when the tape is held at the perforating station 53 against movement, the drive belt 227 is permitted to slip over the pulley 225. Thus it will be seen that a more or less constant tension is applied to the tape, tending to assist the driving drum 140 in advancing the tape. The chuck 48 is in the form of a hollow cylindrical drum-like member having a slot 49 therein coextensive with the width of the chuck and into which one

end of the tape may initially be inserted prior to winding of the same on the chuck. A backing flange 51 for guiding the tape extends radially from the chuck at the rear edge thereof.

The chuck 50 is ordinarily not in service during normal tape perforating operations and is employed after the completion of the perforation of a roll of tape for reeling the tape from the roll 41. Accordingly, means are provided whereby the chuck 50 remains at rest during such tape perforating operations and whereby the chuck may be set into operation when desired for reeling purposes. Toward this end the chuck 48 is formed with an extension 224 (see Fig. 6) in the form of a stub shaft which projects through the hollow bracket 46 and is rotatably journaled in the opposite sides thereof by means of a pair of bushings 226 and 228 respectively. A pulley 230 surrounds the bushing 226 and is freely rotatable thereon. A drive belt 232 passes over the pulley 230 and extends downwardly into the casing 18 and is operatively associated with the motor M. Keyed to a reduced portion 236 formed on the stub shaft 224 is a rotatable sleeve 238 having a series of peripheral openings 240. Surrounding the sleeve 238 and rotatable therewith is a laterally shiftable face member 242 having laterally projecting clutch teeth 244 formed thereon adapted to extend through the openings in the sleeve 238. The clutch teeth 244 are designed for cooperative engagement with a series of indentations 250 formed in one side of the pulley 230. The member 242 is provided with an annular groove 252 therein adapted to receive one end of a clutch shifting spring 254 which is anchored as at 256 and biased in such a direction that the shiftable clutch collar 242 is normally moved out of engagement with the pulley 230. Pivoted as at 260 to one wall of the bracket 46 on the inside thereof is an arcuate-shaped arm 262 having an operating lever 264 which projects outwardly through a slot 266 in the top wall of the casing 46. The extreme inner or free end of the arm 262 is provided with a cam depression 268 upon which the spring 254 is adapted to ride when the operating lever is moved to one of its extreme positions, thus allowing the clutch collar 242 to be withdrawn from engagement with the pulley 230. Upon movement of the operating lever 264 to its other extreme position, the spring 254 will ride out of the depression 268 and cause the clutch collar 242 to be moved into engagement with the pulley 230 to impart motion to the chuck 48 from the pulley 230.

The chuck 42 is substantially identical in its construction with the chuck 50 and similar characters of reference have been applied to the corresponding parts of the two chuck assemblies. The chuck is driven from the jack shaft 212 by means of a driving belt 270. During normal tape perforating operations the lever 264 is shifted to its neutral position so that the tape T may be withdrawn from the roll 40 as required at the perforating station 53. However, where it is required to reverse the movement of the tape to any considerable extent the lever 264 may be moved to its operative position whereupon the chuck 42 is rotated in such a direction that the tape may be taken up on the roll 40.

The fresh rolls of tape 40 prior to their installation in the machine as they are received from stock are in the form of a relatively small cardboard core upon which the tape is spirally wound. The diameter of the chucks 42 and 50

are substantially equal to the internal diameter of the aforesaid cardboard cores while the overall diameter of the rolls is ordinarily approximately ten inches. In order that the rolls may be applied to and withdrawn from the chucks 42 and 50, an ejecting mechanism is associated with each of these chucks. This ejecting mechanism is best illustrated in Fig. 8 wherein the chuck 42 proper is shown in detail. The chuck 42 includes a cylindrical body portion 272 having formed therein a pair of longitudinally extending spaced parallel slots 274. A pair of U-shaped spring tension members 276 have their ends frictionally held within the slots 274 and the outer sides thereof extend inwardly of the chuck 42 in spaced relation to the cylindrical body portion 272. The free sides of the member 276 diverge slightly from the cylindrical surface of the body portion 272 but are adapted to be brought into parallelism when the cardboard form upon which the roll of tape is mounted is frictionally inserted thereover. In order that the cylindrical shape of the roll 40 will not be distorted by an attempt to remove the roll manually from its frictional engagement with the chuck 42, a pair of ejecting fingers 280 are pivoted as at 282 within a slot 284 formed adjacent the rear of the chuck body. The chuck is formed with a rear guide plate 286 which is slotted as at 288 and the fingers 280 normally occupy a position within the slots 288 and flush with the surface of the plate 286. The fingers 280 are formed with inwardly extending protuberances 290 adapted to be engaged by the inner end of a plunger 292 slidably disposed within a bore 294 formed longitudinally in the body portion 272. The plunger 292 is provided with a head 296 in the form of a finger release button which upon being engaged by the finger of the operator forces the plunger 292 inwardly into engagement with the protuberances 290 so that the ejecting fingers 280 move forwardly and emerge from the slot 288 to force the cardboard form on which the roll of tape is mounted loose from the chuck.

Referring now to Figs. 3 and 4, in order to hold the tape firmly against the bed plate 52 and thus insure proper registry of the driving pins 146 and the perforations *d* in the tape, a pressure plate 300, which is preferably in the form of a substantially rectangular block of transparent material, is positioned above the bed plate 52 in the vicinity of the driving drum 140. The plate 300 is secured in position by means of a fastening strip 302 extending along one edge thereof which is pivoted as at 304 between a pair of upstanding flanges 306 formed on a U-shaped bracket 308. The plate 302 is formed with a bifurcated extension 310. The pressure plate 300 is adapted to be moved from an operative position, wherein it is substantially flush with the upper surface of the bed plate 52, to the dotted line position thereof as shown in Fig. 3 wherein it is slightly elevated from the bed plate. Toward this end a spring pressed plunger 312 projects upwardly through an aperture 314 formed in the bed plate and tends to normally urge the pressure plate into its elevated position. An operating lever 316 is pivoted as at 318 between the two upstanding flanges 306 of the bracket 308 and carries a cam or lug 320 which is movable with the lever from an inclined position as shown in dotted lines wherein it is out of engagement with the extension 310 to a vertical position as shown in full lines wherein it is in engagement with the extension 310 and wherein it serves to elevate

this latter extension and force the pressure plate 300 downwardly against the tape.

In order that the tape T may clear the pins 146 for purposes of removal of the tape from beneath the pressure plate 300 and die block 10, a substantially flat, relatively thin leaf spring 322 is secured to the bed plate 52 on the upper side thereof and underlies the tape. The leaf spring 322 is provided with an opening 324 through which the driving pins 146 may project and it is also provided with a yieldable tape-lifting flange 325 which normally occupies a position slightly out of the plane of the upper surface of the bed plate but which is adapted to be forced into this plane by the pressure plate 300 acting through the tape when the pressure plate is moved to its operative position. The pressure plate 300 is formed with a shallow groove 326 to afford a clearance for the driving pins 146 when these latter pins project upwardly above the level of the upper surface of the bed plate 52.

In the operation of the apparatus, a fresh roll 40 is inserted upon the chuck 42 manually by the simple expedient of inserting the cardboard core thereof over the spring retaining fingers 276. When the cardboard form is forced completely home on the chuck the spring fingers 276 will retain the same frictionally against dislodgment. The end of the tape is threaded through the roller guide assembly 36 and beneath the tape tensioning device 38 on the rear side of the casing 22. The lever 316 is moved to its left-hand position, as viewed in Figs. 1 and 3, so that as a consequence the pressure plate 300 becomes elevated to its dotted line position. The tape is then inserted into the narrow slot existing between the die block 10 and bed plate 52 and cover the leaf spring 322 and beneath the pressure plate 300. The tape is then threaded through the other roller guide assembly 36 and beneath its tensioning device 38 and the extreme end of the tape is fitted into the slot 49, in the chuck 48. The chuck 48 is then given a few turns manually to start the tape properly after which the same may be released. It is to be noted at this point that although the chuck 48 normally rotates, the same may be temporarily stopped for the purpose of tape insertion by the simple expedient of grasping the same manually and holding it against rotation, during which time the cord or belt 227 will slip upon the pulley 225. Upon manual release of the tape, the chuck will pick up the same, so to speak, and draw the same from the roll 40. However, at this point the lever 316 is moved to the right, as viewed in Fig. 3, whereupon the pressure plate 300 is moved downwardly to its full line position substantially flush with the bed plate 52 to engage or clamp the tape and force the same over the upper ends of the driving pins 146. The tape is then ready for operative perforation and prior to connecting the machine to any outside operating mechanism or prior to actuating the keyboard 130 the spacing key 134 may be depressed a few times to energize the driving hole perforating magnet 112 and the tape driving magnet 110 until such time as the perforations formed in the tape have advanced into registry with the tape driving pins 146.

If at any time during the operation of the machine it is desired to sever the perforated tape and retain the same as an independent record, the last few character items representing data punched upon the tape may be advanced with the tape to a position wherein it has moved out from underneath the edge of the pressure plate 300.

Using the rear edge of the pressure plate 300 as a tear-off edge, the tape may be severed and pulled from the roller guide assembly 36 and the severed edge attached in any suitable manner to a cardboard ring or form and the form inserted upon the chuck 50. The lever 264 may be then thrown to its operative position wherein the chuck 50 is driven by the drive belt 232 and the tape will then be wound on the form. The same procedure is followed after an entire roll of tape has been consumed. The cardboard form which is left from a used roll of tape may be stored for future use on the chuck 50.

The invention is not to be limited to the exact arrangement of parts shown in the accompanying drawings or described in this specification as various changes in the details of construction may be resorted to without departing from the spirit of the invention. Only insofar as the invention has been particularly pointed out in the accompanying claims is the same to be limited.

What is claimed is:

1. In a tape perforating mechanism, a perforating station, a punching die and a plurality of cooperating tape perforating punches at said perforating station, one of said punches being adapted to perforate driving holes in the tape, a tape driving mechanism designed for cooperation with the driving holes produced in the tape by said punch, a control magnet having an armature for operating said drive hole perforating punch, a control magnet having an armature for operating said tape driving mechanism, means electrically connecting said magnets for simultaneous energization thereof, and means mechanically interengaging said magnet-armatures for substantially simultaneous operation thereof.

2. In a tape perforating mechanism, a perforating station, a punching die and a plurality of cooperating tape perforating punches at said perforating station, one of said punches being adapted to perforate driving holes in the tape, a tape driving mechanism designed for cooperation with the driving holes produced in the tape by said punch, a control magnet for operating said drive hole perforating punch including an armature having an extension thereon designed for contact with said punch, a control magnet having an armature for operating said tape driving mechanism, an extension on said control magnet-armature, said first mentioned extension on the drive hole perforating magnet-armature underlying said last mentioned extension on the tape driving punch and adapted to engage the latter and move the same upon energization of the drive hole perforating magnet.

3. In a tape perforating mechanism, a perforating station, a punching die and a plurality of cooperating tape perforating punches at said perforating station, one of said punches being adapted to perforate driving holes in the tape, a tape driving mechanism designed for cooperation with the driving holes produced in the tape by said punch, a control magnet for operating said drive hole perforating punch including an armature having an extension thereon designed for contact with said punch, a control magnet for operating said tape driving mechanism, an extension on said control magnets, said first mentioned extension on the drive hole perforating magnet underlying said last mentioned extension on the tape driving control magnet and adapted to engage the latter and move the same upon energization of the drive hole perforating magnet, and means

electrically connecting said magnets for simultaneous energization thereof.

4. In a tape perforating apparatus, the combination with a tape perforating punching die having a series of holes therein designed for co-operation with a series of respective punches at a perforating station, of an inverted transparent cup-shaped retaining member secured to and overlying the punching die and creating in combination therewith a suction chamber into which tape punchings are projected during the tape punching operation and through which transparent member and suction chamber the tape is visible, a conduit for removal of said punchings communicating with the interior of said chamber and leading to a point remote from said perforating station, a receptacle for receiving the punchings into which said conduit extends, a suction pump, and means connecting said receptacle to the inlet side of said suction pump.

5. A roller guide assembly for tape perforating machines comprising a U-shaped bracket having parallel sides and a base portion, a cylindrical roller mounted for rotation between said sides and over which the tape is adapted to pass during tape perforating operations, a follower member comprising an operating shaft extending across said sides in close proximity to said roller and projecting completely through said sides and a tape tensioning member secured to said shaft adjacent one of said sides on the outside of said bracket and having a portion extending over said side and movable inwardly toward the base of said bracket for engaging the tape and tensioning the same against said base.

6. In a tape perforating mechanism, a perforating station, a punching die and a plurality of cooperating tape perforating punches at said perforating station, tape driving instrumentalities for advancing the tape through said perforating station, a thrust rod for each of said tape perforating punches and having one end thereof normally in engagement with the latter, a control magnet for each of said thrust rods, a movable armature for each magnet, a contact portion on each armature, said contact portions being normally spaced from the other ends of their respective thrust rods and adapted upon energization of their controlling magnets to move into engagement with said ends and actuate the thrust rods, and means for selectively energizing said control magnets.

7. In a tape perforating mechanism, a perforating station, a punching die and a plurality of cooperating tape perforating punches at said perforating station, tape driving instrumentalities for moving the tape through said tape perforating station, a plurality of substantially vertically disposed thrust rods each having its upper end normally in engagement with a respective punching die, a control magnet for each thrust rod, a movable armature for each control magnet, a contact portion on each of said armatures, said contact portions underlying and being normally spaced a slight distance from the lower end of the respective thrust rod whose movements it controls and being operable upon movement from a retracted position to an advanced position during energization of its respective magnet to engage the lower end of its respective thrust rod and force the same upwardly to perform an operative tape perforating function.

8. In a tape perforating mechanism, a perforating station, a punching die and a plurality of cooperating tape perforating punches at said per-

forating station, tape driving instrumentalities for advancing the tape through said perforating station, a thrust rod for each of said tape perforating punches and having one end thereof normally in engagement with the latter, a control magnet for each of said thrust rods, a movable armature for each magnet, a contact portion on each armature, said contact portions being normally spaced from the other ends of their respective thrust rods and adapted upon energization of their controlling magnets to move into engagement with said ends and actuate the thrust rods, means for selectively energizing said control magnets, and means for varying the effective length of each of said thrust rods.

9. In a tape perforating mechanism, a perforating station, a punching die and a plurality of cooperating tape perforating punches at said per-

forating station, tape driving instrumentalities for advancing the tape through said perforating station, a thrust rod for each of said tape perforating punches and having one end thereof normally in engagement with the latter, an abutment head adjustably mounted on the other end of each thrust rod, a control magnet for each of said thrust rods, a movable armature for each magnet, a contact portion on each armature, said contact portions being normally spaced from the abutment heads on the respective thrust rods whose movements they control and adapted upon energization of the control magnets to move into engagement with said heads and actuate the thrust rods, and means for selectively energizing said control magnets.

WARD LEATHERS.
